UNITED STATES PATENT OFFICE.

WILLIAM STAMP, OF SUSQUEHANNA DEPOT, PENNSYLVANIA, ASSIGNOR OF
ONE-THIRD TO M. B. WRIGHT, OF SAME PLACE.

CAR-COUPING.

SPECIFICATION forming part of Letters Patent No. 309,169, dated December 9, 1884.

Application filed April 21, 1884. (No model.)

To all whom it may concern:

Be it known that I, WILLIAM STAMP, of Susquehanna Depot, in the county of Susquehanna and State of Pennsylvania, have invented
5 a new and useful Improvement in Car-Couplings, of which the following is a full, clear, and exact description.

Reference is to be had to the accompanying drawings, forming a part of this specification, 10 in which similar letters of reference indicate corresponding parts in all the figures.

Figure 1 is a sectional side elevation of my improved car-coupling, taken through the line *z z*, Fig. 2. Fig. 2 is a front elevation of one 15 part of the same, the coupling-link being shown in section. Fig. 3 is a sectional plan view of the same, taken through the line *x x*; Fig. 2. Fig. 4 is a sectional side elevation of a part of the same, taken through the line *y y*, Fig. 2.
20 The object of this invention is to facilitate the coupling and uncoupling of cars in making up and breaking trains, and promote convenience and safety in said operations.

The invention consists in the construction 25 and arrangement of parts, as will be herein-after fully described and claimed.

A represents the draw-head of the coupling, the draw bar or body B of which is connected with the car-body C in the ordinary manner. 30 The draw-bar B is designed to be made of wrought-iron, and to have the draw-head A cast upon its forward end. The mouth D of the draw-head A is made hopper-shaped to guide an entering link, E, into place, and is made 35 sufficiently large to allow the interior separable parts of the coupling to be put in and taken out through the said mouth, so that a broken part can be taken out and replaced by a new part through the said mouth.

40 Within the draw-head A is formed a large space, F, to receive the inner end of the link E and the movable arms (hereinafter described) of the coupling, and allow the said parts to have the necessary freedom of movement. The forward upper part of the space F is curved upon the arc of a circle, and the forward side of the upper part, G, of the coupling-pin is correspondingly curved to provide a firm support for the said part of the pin when 45 sustaining a draft-strain, and to allow the said part of the pin to move up and down freely.

Upon the lower part of the forward side of the part G of the pin is formed a shoulder, H, which, when the said part G of the pin is under a draft strain, rests against the draw-head A 55 at the upper side of its throat, to prevent the said part of the pin from rising and releasing the coupling-link E. The upper part, G, of the coupling-pin is formed upon the forward end of the arm I, or has a socket in its rear 60 side to receive a head formed upon the said forward end of the arm I. The rear part of the arm I is curved downward, and its rear end is enlarged and has a semi-cylindrical hole, J, formed through it to receive the semi-cylindrical shaft K, which passes through a cylindrical hole, L, in the draw-head A. The hole J is made larger than the shaft K, so that the said shaft can have a slight rotary movement within the said hole. The hole L is made 70 larger than the shaft K, so that the entire draft-strain will come upon the forward part of the draw-head, and so that the part G of the coupling-pin and its arm I can be pushed back in coupling and uncoupling the cars, 75 to free the shoulder H from the draw-head A, and allow the said part of the pin and its arm to rise.

M is the lower stationary part of the coupling-pin, which projects upward and rearward, 80 so as to be met by the upper movable part, G, as shown in Figs. 1 and 2. The part M of the pin can be formed solid upon the lower part of the draw-head A, or it can be made of wrought-iron or cast-steel and the draw-head 85 A cast upon its lower part, as indicated in dotted lines in Fig. 1.

At the side of the arm I is placed an arm, N, which has a semicircular hole, O, in its rear end to receive and fit upon the shaft K. 90 The arm N is curved forward and downward, and is made of such a length that its forward end will rest upon the inner end of the link E. The lower end, N', of the arm N is extended downward and forward, and passed beneath the end of the link E, and when the arm N is raised the lower end, N', of the said arm will raise the said end of the link E above the stationary part M of the coupling-pin, so that the link will be free to draw out when 95 the cars are drawn apart.

To the end of the shaft K is attached a crank,

P, the shank of which is made of such a length that the arm of the said crank will be about in line with the side of the car-body C, so that the said crank can be operated from the side of the track. With this construction, by a slight movement of the crank P the outer end of the link E can be raised more or less to guide the said outer end of the link into the mouth of the draw-head of an adjacent car, 5 the enlarged hole J in the arm I allowing this to be done without moving the said arm I and the part G of the coupling-pin connected with it. When the cars are run together, the end of the entering link E strikes and slides 10 up the lower stationary part, M, of the coupling-pin, and then strikes the upper movable part, G, of the said pin, pushes it back far enough to free the shoulder H from the draw-head A, and then forces the said part G upward and passes its lower end, the said end 15 of the link E dropping over the said stationary part M of the pin by its own weight, and the said upper part, G, dropping upon the said lower part, M, coupling the cars. The 20 part G of the pin is raised to uncouple the cars by operating the crank P. The outer part of the crank P is supported by a bracket, Q, attached to the car-body, and which is made with a downward bend, R, to support the 25 crank when the parts of the coupling are in a coupled position. The bracket Q is made with a horizontal bend, S, in its forward part to receive the shank of the crank P. The bend S is made narrow, and the part P' of the shank 30 of the crank that enters the said bend is flattened to fit into the said bend, so as to be held from turning. The shank of the crank P is flattened in such a direction that it will enter the bend S only when the crank P has been 35 turned into such a position as to raise the arm I and part G of the pin into the uncoupled position, where they will be securely held, so that the cars can be run together without coupling. 40

45 This improvement is especially convenient

in making up trains, as it enables the man making up the train while the car is passing him to throw the crank P into position to cause the cars to couple, or to remain uncoupled when they are run together. 50

Having thus described my invention, I claim as new and desire to secure by Letters Patent—

1. The combination, with the draw-head provided with the inclined part M, and the recess F, of the arm I G, formed with the shoulder H on its upper forward end, and apertured at its rear end, and a shaft, K, pivoted in enlarged bearings L in the draw-head, and passing through the apertured end of the arm, whereby the arm I may be moved longitudinally until its shoulder H is out of contact with the draw-head, and then vertically into the recess F, substantially as set forth. 55

2. The combination, with the draw-head A, provided with the inclined part M of the arm I G, having an enlarged slot, J, at its rear end, the arm N, provided with the forwardly-projecting lower arm, N', and a slot, O, and the shaft K, journaled in the draw-head, and passing through slots J O, said shaft being of the same 60 size as the slot O, but smaller than the slot J, whereby the arm N' may be operated, as described, without affecting the arm I, for guiding the coupling-link to another draw-head, substantially as set forth. 75

3. In a car-coupling, the combination, with the car-body and the crank P, connected with the rock-shaft that operates the coupling and guiding-arms, and having a flattened part, P', of the bracket Q, having a downward bend 80 and a horizontal bend, substantially as herein shown and described, whereby the coupling can be readily set to couple or remain uncoupled when the cars are run together, as set forth.

WILLIAM STAMP.
